UNITED STATES PATENT OFFICE.

ELBERT FOWLER, OF BALTIMORE, MARYLAND, ASSIGNEE, BY MESNE ASSIGNMENTS,
TO GEORGE RAWAK, OF NEW YORK, N. Y.

ELECTRIC CLOCK.

Application filed July 7, 1919, Serial No. 908,952. Renewed May 5, 1933.

To all whom it may concern:

Be it known that I, ELBERT FOWLER, a citizen of the United States, and residing at Baltimore, Maryland, have invented certain new and useful Improvements in Electric Clocks, of which the following is a specification.

This invention relates to electrically driven clocks, particularly to secondary 10 clocks connected in electrical circuit with a master clock and adapted to be controlled thereby. The secondary clock disclosed herein is particularly adapted to be used as a wall clock in apartments, hotels, factories 15 and public buildings, in which such clocks are located in partitions and have two dials, one facing in each of two adjoining rooms, but it may also be used in single faced 20 clocks, tower clocks, ordinary mantel clocks, desk clocks, or clocks intended for special purposes.

The objects of this invention are to provide a clock of this class in which by novel 25 arrangement of gearing and electromagnetic apparatus for actuating the gearing a clock is provided which is composed of a minimum number of parts, in which the parts are of extremely simple construction, and in which the use of springs and other delicate 30 and perishable elements is avoided. As a result of my novel construction, it is possible to construct the mechanism and assemble the same at less cost and with greater ease than other clocks of this character heretofore designed or suggested. It is also possible to make the clock of much smaller size 35 than has heretofore been found necessary, thus enabling it to be conveniently placed in a very thin wall between two rooms and allowing desk clocks, mantel clocks, &c., of small size to be constructed.

It is a further object of the invention to provide a novel casing of very simple construction consisting of two similarly shaped 45 portions adapted to contain the gearing and to form a dustproof protection therefor, the two portions being held together by an element of the electromagnetic apparatus, in this case by a U-shaped electromagnet for 50 operating the gearing, which thereby performs two functions and obviates the use of bolts, screws, or rivets which would otherwise be necessary to secure the two halves of the casing together.

The invention will be fully disclosed in 55 the following description when taken in connection with the accompanying drawings, in which—

Fig. 1 is a side elevation of the clock, the hands and dials being omitted;

Fig. 2 is a plan view, a portion of the casing being broken away and a portion of the mechanism being indicated in dotted lines;

Fig. 3 is a side elevation as seen from the side opposite that shown in Figure 1, part 60 of the casing being broken away;

Fig. 4 is a section on the line 4—4 of Figure 3;

Fig. 5 is a section on the line 5—5 of Figure 4;

Fig. 6 is a perspective view of one-half of the casing;

Fig. 7 is an enlarged view of the pawl and ratchet mechanism;

Fig. 8 is a detail of one of the bearings. 75

A horizontally disposed worm A which is hereinafter described as the "drive worm" is mounted on or integral with the horizontal shaft S, the ends of which bear in suitable recesses in the elongated members 80 U hereinafter to be described. The worm A has a double thread and is adapted to be intermittently rotated by the electromagnetic actuating apparatus to drive the hands of the clock through intermediate gearing. 85 Meshing with the threads of drive worm A are the teeth of three worm wheels A', A² and A³ each having twenty four teeth, and as the worm A rotates, these three worm wheels will each rotate at one-twelfth the angular velocity of the worm A. The worm wheels A' and A² are mounted respectively on the horizontally disposed minute hand shafts M' and M², and the worm wheel A³ is mounted on a shaft S' at its central point, 90 there being located above and below the wheel A³ and concentric therewith on this shaft, the worms B and B', the upper worm B having two threads with right hand twist and the lower worm B' having two threads 95 with left hand twist.

Meshing with the worms B and B' are two worm wheels B² and B³ respectively, each provided with twenty four teeth. The worm wheel B² is mounted upon a solid 100 shaft H, to the outer end of which is connected the hour hand of the right hand clock (Fig. 5) the dial of which is repre-

sented at D, and the worm wheel B³ is mounted upon the hollow shaft H' to the outer end of which is connected the hour hand H³ of the left hand clock (Fig. 5).

- 5 As each of worms B and B' contain two teeth and worm wheels B² and B³ contain twenty-four, these worm wheels will be rotated by the worms respectively at one-twelfth the speed of rotation of the latter.
- 10 The hollow shaft M' and the solid shaft M² upon which the worm wheels A' and A² respectively are mounted, support at their outer ends the minute hands M³ and M⁴ of the oppositely facing clocks. The concentric 15 shafts leading to each dial are freely rotatable relatively to each other, and the hollow shaft turn freely in the bearings in the casing.

Electromagnetic means is provided for intermittently rotating the drive worm A. This mechanism is clearly illustrated in Figures 2, 3, 4 and 7. Rigidly mounted on the shaft S at one end of the worm A, is a ratchet R which is rotatable in one direction only, the pawl P supported upon the pivot P' attached to the casing preventing backward movement of the ratchet, as seen in Figure 7. The pawl P has its lower end provided with a weight P⁴ and is not dependent 30 on spring pressure to hold it in place. A soft iron member or armature K is secured to a sleeve K' mounted upon shaft S, and freely rotatable thereon. The armature K has a projection K² to which a pawl K³ is pivoted and as the armature is oscillated about its pivotal point, the pawl K³ operating upon the ratchet R imparts a step by step motion to the shaft S and the worm A. The pawl K³ which is freely rotatable on its supporting pivot K⁴ extends laterally from the armature K, and has a lower weighted portion K⁵ which maintains the pawl in operative position.

As clearly shown in Figures 3 and 7, the armature K is heavier on one side than on the other, and has a tendency to rotate in a counter clockwise direction. A stop T projecting laterally from the wall of the casing, as clearly shown in Figure 7, limits the 45 movement of the armature in both directions, the inclined face T' of the stop forming an abutment limiting its movement in a counter clockwise direction and the upper face T² forming an abutment limiting its movement in the opposite direction. Pole pieces G and G' extend through the wall of the casing on opposite sides of the shaft S and have curved ends terminating in close proximity to the armature K. These pole 50 pieces are preferably inserts into the halves of the casing which is preferably of light and if possible of non-conducting material and have portions extending laterally which are provided with openings G² and G³ respectively to receive the lower ends of the

cores E and E' of the electromagnet which is provided to intermittently excite and operate the armature K.

This electromagnet is as shown, U-shaped, the cores E and E' being integral with the yoke portion E² and the coils E³ and E⁴ being securely fastened to the core portions E and E' respectively.

Suitable electric connections are made from a relay or master clock, not shown, to the coils E³ and E⁴. When these coils are excited, the armature K immediately assumes a horizontal position, thereby rotating the ratchet wheel R and the worm A. When the circuit through the electromagnet is broken, the armature K immediately drops back to the position shown in Figure 3, the pawl K³ slipping back one tooth, and being in position upon the next movement of the armature to again rotate the ratchet wheel and the worm A.

The ratchet wheel R is provided with ten teeth and in the present arrangement is adapted to be rotated one-tenth of a revolution every thirty seconds under control of the master clock. Thus the worm wheel A will make twelve revolutions per hour, the minute hands will make one revolution per hour, and the hour hands will make one-twelfth of a revolution per hour.

The casing as shown comprises two exactly similar or duplicate half portions L and L', provided with extended bearing portions L² and L³ respectively to support shafts on which the hands are mounted, and lugs L⁴ and L⁵ adapted to cooperate with the projections L² and L³ in holding between them the coils E³ and E⁴ of the U-shaped electromagnet. In this way the electromagnet, which is also held in place by leaf springs J and J', serves two functions, that of operating the armature K, and that of serving as a means for holding the two halves of the casing together, thus avoiding the use of other securing means, such as bolts or screws and rendering the device simpler and more convenient to disassemble for the purpose of inspection and repair.

The ends of shafts S and S' are, as above mentioned, mounted in members U and U' respectively, which fit closely into the channels formed in the bosses V in the inside of the casing. This arrangement is provided so that the castings for the two halves of the casing may be exactly similar, and also for the purpose of providing additional means for locking the two sections against lateral movement. Dowel pins W on each section cooperating with holes W' on the opposite section, are also instrumental in holding the sections of the casing in their proper relative positions.

It will be apparent that the mechanism contained in the casing is of extreme simplicity, the parts being few in number, small

in size, and comprising no delicate springs or perishable elements such as are common in clocks of this class now on the market. The mechanism is so designed and constructed that it will operate for long periods of time without attention, and the entire structure is so designed, that by removing the U-shaped armature, the casing can be disassembled quickly, and the parts easily inspected. In case it is necessary to replace a part, this can be done quickly and easily due to the manner in which the mechanism is supported.

Although I have described and illustrated my invention as particularly applicable to wall clocks, I do not limit myself to such use inasmuch as the invention may be conveniently used in connection with desk clocks, mantel clocks, tower clocks, and other special clocks, and the various details of construction may be modified to suit the particular use to which it is to be put. The scope of the invention will be indicated by the appended claims.

25 What I claim as my invention and desire to secure by Letters Patent is:

1. In an electrically driven secondary clock, in combination, a drive worm, electrical means for giving said worm a rotary movement, a second worm, a worm wheel connected to said second worm and adapted to be driven by said drive worm, a worm wheel connected to the minute hand of the clock and arranged to be driven by said drive worm, and a worm wheel connected to the hour hand of the clock and arranged to be driven by said second worm.

2. In an electrically driven secondary clock, in combination, a drive worm, electrical means for giving said worm a rotary movement, a second worm, a worm wheel rigidly secured to said second worm and adapted to be driven by said first worm, hour and minute hands, a worm wheel connected to the minute hand and arranged to be driven by the drive worm, and a worm wheel connected to the hour hand and arranged to be driven by the second worm.

3. In an electrically driven secondary clock, in combination, a drive worm, electrical means for giving said worm a rotary movement, a second worm, a worm wheel rigidly secured to said second worm and adapted to be driven by said first worm, hour and minute hands, concentric shafts each supporting one of said hands, a worm wheel mounted on one of said shafts and arranged to be rotated by said drive worm, and a worm wheel mounted on the other of said shafts and arranged to be driven by said second worm.

4. In an electrically driven secondary clock, in combination, a drive worm, electrical means for giving said worm a rotary movement, a second worm with its axis at

right angles to the axis of the drive worm, a worm wheel secured to and having its axis coincident with the second worm, a worm wheel connected to the minute hand of the clock and arranged to be driven by the drive worm, and a worm wheel connected to the hour hand of the clock and arranged to be driven by said second worm, the axes of said two last mentioned worm wheels being coincident and at right angles to the axis of each of the two worms.

5. In a clock, in combination, a drive worm, means for giving said worm a rotary movement, a second worm, a worm wheel connected to said second worm and adapted to be driven by said first worm, a worm wheel connected to the minute hand of the clock and arranged to be driven by said drive worm, and a worm wheel connected to the hour hand of the clock and arranged to be driven by said second worm.

6. In an electrically driven secondary clock, in combination, a horizontally disposed drive worm, electromagnetic means for giving said worm a rotary movement, a second vertically disposed worm, a worm wheel concentric with and connected to said second worm and arranged to be driven by said drive worm, concentric shafts disposed with their axes at right angles to the axes of both of said worms and having hour and minute hands thereon, a worm gear mounted on and secured to the minute hand shaft and meshing with the drive worm and a worm gear mounted on and secured to the hour hand shaft and meshing with said second worm.

7. In a clock having two dials, in combination, a drive worm, means for giving said worm a rotary movement, a second worm, a worm wheel connected to said second worm and adapted to be driven by said drive worm, two sets of hour and minute hands, two sets of concentric shafts for supporting and rotating said hands, and a worm wheel on each of said shafts, the worm wheels on the minute hand shaft meshing with and being rotated by said drive worm and the worm wheels on said hour hand shafts meshing with and being rotated by said second worm.

8. In an electrically driven secondary clock in combination, a drive worm, electrical means for giving said worm an intermittently rotary movement, a second worm, worm wheels intermeshing with said drive worm and adapted to be driven thereby, one of said worm wheels being secured to and adapted to drive the second worm, and a second worm wheel being directly connected to the minute hand of a clock, and a worm wheel connected to the hour hand of a clock and arranged to be driven by said second worm.

9. In an electrically driven secondary clock, in combination, a drive worm, means for rotating said worm, a second worm, 130

means connecting said worms whereby the second worm is rotated simultaneously with the first worm, means connected to one of the hands of the clock and arranged to be driven by first worm, and means connected to the other hand of the clock and arranged to be driven by said second worm.

10. In a secondary clock, in combination, a drive worm, means for rotating said worm, 10 a second worm, means connecting said

worms whereby the second worm is rotated simultaneously with the first worm, a worm wheel connected to the minute hand of the clock and arranged to be driven by one of said worms, and a worm wheel connected to 15 the hour hand of the clock and arranged to be driven by the other worm, for the purpose set forth.

In testimony whereof I affix my signature
ELBERT FOWLER.
